UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,752.

To all whom it may concern:

Be it known that I, MOSES F. CARR, a citizen of the United States, and a resident of Newton, in the county of Middlesex, 5 Commonwealth of Massachusetts, have invented an Improvement in Fasteners, of which the following description, in connection with the accompanying drawings, is a specification, like characters on the drawings representing like parts.

This invention pertains to improvements in fasteners, and more particularly, though not exclusively, to fasteners of the three-side lock type. It is among the objects of 15 the invention to provide an improvement in the securing of the sockets of three-side lock fasteners to their carrying fabrics.

In the drawings, which show a preferred embodiment of one form of my invention:—

20 Figure 1 is a front elevation of a socket, a portion of the carrying fabric being shown;

Fig. 2 is a section on the line 2—2 of Fig. 1;

25 Fig. 3 is a diagrammatic section illustrating the portions of the fastener prior to securing thereof to the carrying fabric and illustrating a preferred form of die for effecting the securing operation; and

30 Fig. 4 is a section through the socket on the line 4—4 of Fig. 2.

Referring to the drawings and to the preferred form of my invention selected for illustrative purposes, I have shown a socket 35 which preferably, as illustrated, includes a casing 5 containing a spring 6 and provided with a front plate 7. The casing 5 is preferably provided with a stud-receiving opening 8, and provided with an underlying lip 9. The stud-engaging portion of the spring 6 intersects a portion of this stud-receiving opening so that the spring may engage the neck of the stud beneath the head thereof to hold the stud and socket in engagement.

40 The front plate 7 of the casing is preferably, as illustrated, provided with a forward extension 10 having an inwardly flanged lip 11 and providing an aperture to receive the tubular rivet 12 projecting from 45 the securing means on the other side of the socket-carrying fabric 13.

The securing means preferably includes a plate 14, from which the tubular rivet 12 projects, and a covering plate 15. The plate 55 14, prior to assembly of the parts, is prefer-

ably dished in the direction of the projection of the tubular rivet 12, as best shown in Fig. 3, and the marginal portions thereof of underlie the flange 16 of the covering plate 15, closely fitting the same. When the 60 parts are to be assembled they are placed in the relationship shown in Fig. 3 and the upsetting die 17 is introduced through the stud-receiving aperture of the socket, the head thereof being preferably rounded to 65 move the stud-engaging spring out of the way. A supporting die 18 backs up the covering plate 15 and, as the two dies are forced together, the plate 14 is sprung so that it dishes in the opposite direction from 70 that illustrated in Fig. 3 and assumes the position shown in Fig. 2 as the tubular rivet is upset by the die 17. The upsetting of the rivet holds the parts in assembled relationship, and the reversal of the dishing of the 75 plate carrying the tubular rivet results in great pressure being exerted to grip the cloth between the marginal portions of the socket and the marginal portions of the socket-securing parts on the opposite side 80 of the fabric 13.

When the die 17 is removed after the completion of the socket-securing operation, the stud-engaging spring resumes its normal position and the socket is ready for use. 85 When the stud is entered in the socket, the head of the stud may engage the projecting portion 10 of the socket casing. I have not described the operation of the stud and socket more fully, such description being unnecessary because, so far as the cooperation of the stud and socket is concerned, the construction is fully described in United States Patent No. 1,278,798, issued September 10, 1918, to Carr Fastener Company, assignee 90 of Fred S. Carr. It will be understood, however, that my invention may be of use in connection with other types of fastener.

While I have shown and described a preferred form of one embodiment of my invention, it will be understood that major changes involving omission, substitution, alteration and reversal of parts, and even changes in the mode of operation, may be made without departing from the scope of 105 my invention, which is best defined in the following claim.

Claim.
A fastener including a casing located on that side of the socket-carrying fabric from 110

which the stud enters, said casing comprising a plate presenting a forwardly disposed portion presenting an internal flange and securing means on the opposite side of the 5 socket-carrying fabric comprising a covering plate having a convex face adjacent the fabric and a securing plate secured to said covering plate and carrying a tubular rivet for passage through the fabric and adapted

to be riveted over said internal flange, said securing plate prior to assembly with said socket being dished to present a convex surface adjacent the fabric and subsequent to assembly being sprung to provide a concave surface adjacent said fabric. 10
15

In testimony whereof, I have signed my name to this specification.

MOSES F. CARR.
